UNITED STATES PATENT OFFICE.

BARTON S. SNOW, OF BATAVIA, ILLINOIS, ASSIGNOR TO T. W. SNOW CONSTRUCTION CO., OF CHICAGO, ILLINOIS, A CORPORATION OF ILLINOIS.

MATERIAL-ELEVATING APPARATUS.

Application filed October 27, 1922. Serial No. 597,326.

To all whom it may concern:

Be it known that I, BARTON S. SNOW, a citizen of the United States, residing at Batavia, in the county of Kane and State of Illinois, have invented a new and useful Improvement in Material-Elevating Apparatus, of which the following is a specification.

My invention relates to apparatus of the general type commonly used for elevating material such as, for example, coal, from a hopper into which the material is dumped from railway cars located on tracks above the hopper, into a storage bin above the tracks from which the material is permitted to discharge as, for example, into the tenders of locomotives, this type of apparatus comprising a substantially vertically-operating bucket, or skip, for elevating the material into the uppermost hopper and power-operated cable means for operating the bucket.

One of my objects is to provide improvements in apparatus of the type above referred to, and involving a charge-receiving receptacle which operates to receive a charge from the hopper and elevate it to a position for discharge into the bucket or skip, and by which the bucket may be elevated substantially to dumping position at a relatively high speed and the desired deceleration of the bucket at the end of its elevating movement accomplished without undue expenditure of power. Another object is to provide improvements whereby a relatively shallow pit for receiving the bucket when in loading position may be provided. Another object of the invention is to provide for the automatic filling of the bucket, elevating it and dumping its contents into the uppermost hopper and thereafter lowering the bucket and repeating the operation stated, all in an automatic manner. Another object is to provide in apparatus of the general type above referred to, a novel and simple construction of charge-receiving container and one which shall operate in a novel manner; and other objects as will be manifest from the following description.

Referring to the accompanying drawings:

Figure 1 is a view in vertical elevation of a railway coaling station equipped with my improvements, certain of the parts being shown in elevation, this view showing the bucket in lowermost, loading, position and the parts associated therewith and the positions they assume in this position of the

bucket. Figure 2 is a view in end elevation of the structure shown in Fig. 1, certain parts of the structure being shown in section, the apparatus being viewed from the right hand side of Fig. 1. Figure 3 is a section 60 taken at the line 3—3 on Fig. 1 and viewed in the direction of the arrows. Figure 4 is an enlarged elevational view of the lower part of the structure shown in Figs. 1 and 2, with certain parts sectioned, this view showing, by full lines, the position occupied by the parts cooperating with the bucket when the bucket is rising but before it reaches dumping position, and by dotted lines the positions assumed by these parts upon the 70 bucket reaching dumping position. Figure 5 is an enlarged broken sectional view taken at the line 5—5 on Fig. 4 and viewed in the direction of the arrows. Figure 6 is a plan sectional view taken at the irregular line 75 6—6 on Fig. 4 and viewed in the direction of the arrows; and Figure 7, a view like Fig. 4, showing by dotted lines the position occupied by the parts cooperating with the bucket when the bucket is in dumping position and during the descent of the bucket before the latter reaches loading position, and by full lines the position occupied by these parts when the bucket reaches filling position.

The apparatus shown comprises a pit structure which extends below the level at which the tracks, represented at 8 and on which the cars containing the material to be elevated are run, extend, this pit, which 90 is represented at 9, containing a hopper 10 open at its upper end and across which the tracks 8 extend, this hopper being provided for receiving the material from the cars. Rising from the ground adjacent the pit 9 is 95 a frame structure 11 on which is mounted a hopper 12 shown as provided at its outlet with spout-and-valve mechanism, represented at 13, for controlling the flow of material from the hopper 12 into the receptacle to be 100 charged therewith, as, for example, a tender located on the track 14. The hopper 12 and the control mechanism therefor may be of any suitable construction, and as this 105 part of the apparatus is of common construction detail description thereof is unnecessary. The framework 11, at the side of the hopper 12 opposite that at which the device 13 extends, projects upwardly above the hopper 12 which latter communicates with 110

an inlet chute 15 and provides the support and guiding means for a vertically-movable bucket or skip, represented at 16 and provided for the purpose of elevating material from the hopper 10 to a position in which it discharges through the inlet chute 15 into the bin 12. The last-referred-to portion of the framework 11 is provided at opposite sides of the chute 15 with pairs of vertical bars 17 spaced apart to provide guides for the bucket 16. The bucket 16 is of a construction commonly provided in apparatus of this general type, this bucket being provided with a bail 18 pivotally connected at its lower end with the under side of the bucket. The bail is shown as formed of the upper cross-bar 19, the lower cross-bar 20 which extends beneath the bucket 16 and with which the bucket is pivotally connected, and side bars 21 connected with the end portions of the cross-bars 19 and 20, the lower cross-bar 20 being provided with rollers 22 and the side bars 21 with rollers 23 which extend into the vertical guide-ways 17 for guidance. The bucket, as shown, is of such construction that it is overbalanced, tending to tilt on the cross-bar 20 of the bail, to the left in Fig. 1 when in loaded position. The bucket is provided at opposite sides with laterally-extending rollers 24 which bear, under the tilting action of the bucket, against the adjacent vertical guide surfaces 25 of guide bars 26 carried by the framework alone, the upper extremities of these guide bars being curved toward the hopper 12, as represented at 27, and terminating in the substantially horizontally-extending portions 28, whereby when the bucket 16 is elevated to its extreme upper position it will automatically tilt to the left in Fig. 1 at its pivotal connection with the bail 19 and discharge its contents into the chute 15, and in the lowering of the bucket will be automatically rocked to upright condition.

The cable which controls the vertical movement of the bucket 16 is represented at 29, this cable being connected at one end with the upper end of the bail, as represented at 30. The cable extends upwardly from the bail and around a supporting sheave 31 journaled on the framework 11, and thence extends downwardly to a drum 32 upon which it is wound, the drum 32 being a hoisting drum operated from any suitable source of power as from the engine represented at 33. The cable 29 thence passes over a pulley 34 journaled on the framework 11 and thence around pulleys 35 and 36 constituting a block-and-tackle, the pulley 36 being journaled on the framework 11 and the pulley 35 journaled in the upwardly-extending spaced arms 37 of a counterweight 38, the end of the cable 29 opposite the end connected with the bucket 16, as stated, being connected with the framework

at 39. The counterweight 38 is vertically movable, it being guided in its movement in any suitable way, as, for example, by means of the T-bars 40 supported on the framework 11 at opposite edges of the counterweight and extending at portions thereof into vertical grooves 41 contained in opposite edges of the counterweight 38.

It will be understood from the foregoing description that the arrangement of the bucket, counterweight and cable mechanism connecting these parts is such that the counterweight required for producing the counterweighting function, viz., to substantially counterweight only the weight of the bucket plus one-half of the load carried by the bucket, is very much greater than where the counterweight is so connected direct with the bucket, through the cable mechanism, that it travels at the same speed as the bucket, the purpose of providing a relatively heavy counterweight being hereinafter explained.

Cooperating with the hopper 10, the outlet of which is represented at 42, is mechanism 90 for receiving a charge from this hopper, elevating the charge and thereafter dumping it into the bucket 16 when the latter is in the position represented in Fig. 1, a description of this mechanism being as follows: 95 The mechanism referred to comprises the charge-receiving receptacle 43 shown as of general inverted hopper form, viz., to provide a closed bottom, upwardly-converging walls 45 and 46 and substantially parallel 100 side walls 47, the wall 45 containing at its upper end an opening 48 which, in the lowermost position of the receptacle 43, viz., the position represented by full lines in Fig. 4, registers with the outlet 42 of the hopper 10, the opposite inclined wall 46 being open 105 at its lower portion, as represented at 46a, this wall being formed with angularly-disposed portions 49 and 50, the latter being connected with the lower edge of the inclined 110 portion of the wall 46, as shown, whereby the receptacle 43 presents a spout-portion represented at 51. The receptacle 43 is provided with a depending frame structure 52 at which it is pivotally connected, as represented at 53, with the forward extremities of forwardly and downwardly projecting parallel bars 54 forming a part of a carriage structure, these bars being rigidly connected, at their forward and rear ends, to the parallel side bars 55 of the carriage. The carriage also involves a cross-shaft 56 connected with the lower ends of the side bars 55 and equipped with wheels for a purpose herein-after explained, the upper ends of the bar 55 also being provided with wheels 58. The carriage frame thus provided is in the form of a yoke, and for the purpose of stiffening the members 54 struts 59 connected with these members and with the side members 130

- 55 are provided. The receptacle 43 is positioned between the side bars 55 and between the opposing bars 54 and 59, the frame members 52 being located between the members 54 and 59, whereby the receptacle 43 is adapted to be rocked on the carriage at the pivotal connection 53 therewith. The parts just described are so constructed and arranged that the center of gravity of the receptacle 43, 10 when the latter occupies the normal position shown by the full lines in Fig. 1, extends to the left in Fig. 4 whereby the receptacle 43 tends to rotate in counter-clockwise direction in this figure, it being held in the full 15 line position shown, by the engagement of its bottom plate 44 with the axle 56 of the carriage.

The apparatus also involves a pair of parallel, upwardly-inclined tracks 60 located 20 within the pit 9 and extending substantially parallel with and in spaced relation to the front wall 61 of the hopper 10, the carriage for the receptacle 43 being mounted at the rollers 57 and 58 thereof, on these tracks 25 and along which the carriage is movable. Each track 60 at its lower end, is provided with a stop 60^a for engagement with the rollers 57 in the lowermost position of the carriage, viz., that shown by full lines in 30 Fig. 4, in which position the receptacle 43 registers at its inlet 48 with the outlet 42 of the hopper 10 and in such position receives a charge of material from this hopper, each track 60 being provided at its upper end with a projection 62 presenting upwardly-converging slightly recessed surfaces 63 and 64.

The receptacle 43 is provided at its outlet 46^a with a pair of bars 65 located beneath 40 the bottom 44 of the receptacle beyond the lateral sides thereof, these bars being pivotally supported on the ends of a shaft 66 secured to the underside of the receptacle. The bottom wall 44 immediately above the 45 inner ends of the bars 65 is slotted, as represented at 67, to permit these bars to freely rock in clockwise direction in Figs. 4 and 7. Secured to the bottom wall 44 to extend crosswise below its under side, is an 50 angle bar 68, the horizontal flange of which extends into such a position, as shown, as to form an abutment for the inner ends of the bars 65 restraining them against counter-clockwise rotation in Figs. 4 and 7, the purpose of the bars 65 being hereinafter described.

The receptacle 43 is connected, at opposite sides thereof, and to the left of the pivot 53, viewing the structure as shown 60 in Fig. 4, as represented at 69^a, with the lower ends of cables 69 which pass over pulleys 70 journaled on the frame of the structure, the other, depending, ends of these cables being connected with the ends of a cross-bar 71 guidingly confined at its ends

in the guides 25-29. The cross-bar 71 is located below, and in the path of movement of, the bucket 16, and operates as herein-after described.

The receptacle 43, constructed as herein-before described, is, in the operation of the apparatus, moved from the full line, filling, position shown in Fig. 4, to the dotted position therein shown, and thereafter rocked on its pivot to discharge its contents 75 into the bucket 16, and in moving from filling position, operates to cut through the material at the outlet 42 of the hopper 10. In order that this outlet shall be closed except when the receptacle 43 is being charged with material, I provide a 80 slide valve which is movable into and out of a position in which this outlet is closed and operates automatically to close this outlet in the upward movement of the receptacle 43. The construction of slide valve shown involves a plate 72 which extends across the hopper outlet 42 and flatwise opposes the under sides of channel bars 73 secured to the front wall of the hopper 90 10 and located at opposite sides thereof, the channels of these bars facing outwardly. The plate 72 is provided at each end with a pair of brackets 74 in which rollers 75 are journaled, these rollers extending into 95 the channels of the bars 73 and bearing, by rolling contact, upon the upper surfaces of the lower flanges of these bars, whereby the plate 72 is supported to be moved into and out of a position in which the outlet 99 100 105 110 115 120 125 130 42 is closed, there being provided beneath the plate 72, a pair of angle irons 76 stationarily connected with the hopper 10 to aid in the supporting of the plate 72. The valve just described cooperates with weight and pulley mechanism which operates to move the valve to the closed position shown in Fig 7 and which yields to permit of the opening of the outlet 42 when the plate 72 is forced downwardly as hereinafter described. The pulley and weight mechanism referred to involves a pair of cables 77 each connected with one of the forward brackets 75 at each side of the plate 72 and thence extending over pulleys 78 and 79 secured to the hopper 10, the lower ends of these cables being connected with a weight 80. The carriage upon which the receptacle 43 is pivoted, as stated, is connected at its upper end, at opposite sides thereof, with the lower ends of cables 81 which extend upwardly and over pulleys 82 journaled on a stationary part of the structure, the lower, depending, ends of these cables being connected with the ends of a cross-bar 83 guidingly confined between vertical uprights 84 and the portion of the structure to which the T-bars 40 are connected, this cross-bar being located below, and in the path of movement of, the counterweight 130

38. A description of the operation of the apparatus is as follows: Assuming the parts of the apparatus to be in a position in which the charge-receiving receptacle 43 is in lowermost position, as represented by full lines in Fig. 4, in which position it is in communication with the outlet 42 of the hopper 10 and thus receives a charge of material therefrom, the bucket 16 in the 10 position of the receptacle 43, as stated, will be ascending and will be above the dotted position of the bucket shown in Fig. 7. As the bucket 16 continues its upward movement toward dumping position, (the bucket upon reaching the upper end of the 15 guide bar 25 automatically dumping the charge previously introduced therein into the chute 15), the counterweight 38 continues to descend, and as the counterweight 20 nears the limit of its lowermost movement it engages the cross-bar 83, forcing the latter downwardly with the result of drawing the carriage, on which the receptacle 43 is pivoted, in an upward direction along 25 the tracks 60 to a position in which the rollers 58 ride over the projections 62, and the carriage assumes the dotted position shown in Fig. 4, the engagement of the rollers 58 with the projections 62 operating 30 to hold the carriage in the raised position referred to. The bodily movement of the receptacle 43, as stated, operates to cause the rear edge of the receptacle to cut through the material located at the outlet 35 42 of the bin 10, the gate device 72, under the action of the weight 80, closely following the movement of the receptacle 43 and serving to close the outlet 42.

Following the dumping of the contents of 40 the bucket 16 into the chute 15, the bucket descends and the counterweight 38 rises, the carriage, and the receptacle 43 pivoted thereon, remaining in elevated position. As the bucket 16 nears the limit of its descent, 45 it engages the cross-bar 71 with the result of rotating the receptacle 43 at its pivotal connection with the carriage, to the full line position shown in Fig. 7, in which position the bucket 16 extends beneath the outlet 50 of the receptacle 43 in a position to receive the charge from the receptacle which slides into the bucket 16. When the bucket 16 is operated to hoist it to dumping position, the bucket, by engaging with the outer ends of 55 the bars 65 which, in the discharging position of the receptacle 43 overlap the upper edge of the bucket 16, as shown in Fig. 7, first rocks the receptacle 43 from the full line position shown in Fig. 7 to the dotted line position therein shown and in continuing 60 its ascent, operates, by reason of the engagement of the rear end of the receptacle 43 with the shaft 56, to bodily rock the carriage upon which the receptacle 43 is pivoted, in a rearward and upward direction, 65

the carriage turning about the rollers 57 as a pivot. Thus tilting the carriage carries the rollers 58 to a position above the projection 62, and as the counterweight 38 extends out of engagement with the cross-bar 83, the carriage, together with the receptacle 43 pivoted thereon, thereupon runs down the tracks 60 to the dotted position as fast as bar 71 follows the bucket 16 in the upward movement of the latter, the gate device controlling the outlet 42 of the hopper 10 being forced, against the action of the weight 80, to the full line position shown in Fig. 4, in which the outlet 42 is open, by reason of the engagement of the receptacle 43 therewith. 70 75 80

It will be understood from the foregoing that the movement of the receptacle 43 from lower, filling, position to upper, discharging, position is effected by the force exerted by the counterweight 38 in lowering, it being 85 possible by providing the block-and-tackle mechanism hereinbefore described, to provide this counterweight of sufficient weight to actuate the receptacle 43 as stated without exerting an undue amount of lifting force 90 on the bucket 16, it being desirable that the counterweight 38 substantially counterbalance only the weight of the bucket and one-half the load carried by the bucket. 95

The arrangement shown also presents the 100 advantage that inasmuch as the counterweight 38 does not engage the cross-bar 83 until the bucket 16 nears the point at which the latter discharges, and as the weight presented by the charged receptacle 43 is 105 relatively great, the bucket 16 is automatically slowed down before it reaches discharge position. Thus the bucket may be raised at relatively high speed and the speed of its movement is automatically reduced to 110 the desired degree before it reaches dumping position. Furthermore, the counterweight 38 being compounded as explained, by the block-and-tackle, it moves relatively slowly while the bucket 16 moves rapidly, and thus 115 it acts upon the charging receptacle, to raise the latter, at a slow and positive speed.

While I have illustrated and described a particular construction embodying my invention, I do not wish to be understood as 110 intending to limit it thereto as the same may be variously modified and altered without departing from the spirit of my invention.

What I claim as new and desire to secure by Letters Patent is:

1. In material-elevating apparatus, the combination of a hopper for the material to be elevated, an upwardly traveling carriage, a receptacle for receiving and elevating material from said hopper and mounted 120 on said carriage to move thereon into a position in which its contents may discharge therefrom, a movable element into which said receptacle discharges, and means operating responsive to the movement of said 125

element for effecting movement of said receptacle on said carriage to a position in which its contents may discharge.

2. In material-elevating apparatus, the combination of a hopper for the material to be elevated, an upwardly traveling carriage, a receptacle for receiving and elevating material from said hopper and mounted on said carriage to move thereon into a position in which its contents may discharge therefrom, a movable element into which said receptacle discharges, and means operating responsive to the movement of said element for effecting the elevating of said carriage to elevate said receptacle for delivery into said element when moved relative to said carriage.

3. In material-elevating apparatus, the combination of a hopper for the material to be elevated, an upwardly traveling carriage, a receptacle for receiving and elevating material from said hopper and mounted on said carriage to move thereon into a position in which its contents may discharge therefrom, a movable element into which said receptacle discharges, means operating responsive to the movement of said element for effecting movement of said receptacle on said carriage to a position in which its contents may discharge, and means operating responsive to the movement of said element for effecting the elevating of said carriage to elevate said receptacle for delivery into said element when moved relative to said carriage.

4. In material-elevating apparatus, the combination of a hopper for the material to be elevated, an upwardly traveling carriage, a receptacle for receiving and elevating material from said hopper and mounted on said carriage to move thereon into a position in which its contents may discharge therefrom, a movable element into which said receptacle discharges, means operating responsive to the movement of said element for effecting the elevating of said carriage to elevate said receptacle for delivery into said element when moved relative to said carriage, means releasably holding said carriage in elevated position, and means operating responsive to the movement of said element to release said carriage for descent to a position in which said receptacle is charged from said hopper.

5. In material-elevating apparatus, the combination of a hopper for the material to be elevated, an upwardly traveling carriage, a receptacle for receiving and elevating material from said hopper and mounted on said carriage to move thereon into a position in which its contents may discharge therefrom, a movable element into which said receptacle discharges, and means operated by said element in moving toward filling position for effecting movement of said

receptacle on said carriage to a position in which its contents may discharge.

6. In material-elevating apparatus, the combination of a hopper for the material to be elevated, an upwardly traveling carriage, a receptacle for receiving and elevating material from said hopper and mounted on said carriage to move thereon into a position in which its contents may discharge therefrom, a movable element into which said receptacle discharges, means operated by said element in moving toward filling position for effecting movement of said receptacle on said carriage to a position in which its contents may discharge, and means operating responsive to the movement of said element for effecting movement of said receptacle on said carriage out of a position in which its contents discharge.

7. In material-elevating apparatus, the combination of a hopper for the material to be elevated, an upwardly traveling carriage, a receptacle for receiving and elevating material from said hopper and mounted on said carriage to move thereon into a position in which its contents may discharge therefrom, a movable element into which said receptacle discharges, means operated by said element in moving toward filling position for effecting movement of said receptacle on said carriage to a position in which its contents may discharge, and means operated by said element in moving toward dumping position for effecting movement of said receptacle on said carriage out of a position in which its contents discharge.

8. In material-elevating apparatus, the combination of a hopper for the material to be elevated, an upwardly traveling carriage, a receptacle for receiving and elevating material from said hopper and mounted on said carriage to move thereon into a position in which its contents may discharge therefrom, a movable element into which said receptacle discharges, means operating responsive to the movement of said element for effecting the elevating of said carriage to elevate said receptacle for delivery into said element when moved relative to said carriage, means releasably holding said carriage in elevated position, and means operated by said element to release said carriage for descent to a position in which said receptacle may receive material from said hopper.

9. In material-elevating apparatus, the combination of a hopper for the material to be elevated, an upwardly traveling carriage, a receptacle for receiving and elevating material from said hopper and mounted on said carriage to move thereon into a position in which its contents may discharge therefrom, a movable element into which said receptacle discharges, means operating responsive to the movement of said element

for effecting the elevating of said carriage to elevate said receptacle for delivery into said element when moved relative to said carriage, means releasably holding said carriage in elevated position, means operated by said element in moving toward filling position for effecting movement of said receptacle on said carriage to a position in which its contents may discharge, and means operated by said element for releasing said carriage for descent to a position in which said receptacle is charged from said hopper.

10. In material-elevating apparatus, the combination of a hopper for the material to be elevated, an upwardly traveling carriage, a receptacle for receiving and elevating material from said hopper and mounted on said carriage to move thereon into a position in which its contents may discharge therefrom, a movable element into which said receptacle discharges, means operating responsive to the movement of said element for effecting the elevating of said carriage to elevate said receptacle for delivery into said element when moved relative to said carriage, means releasably holding said carriage in elevated position, and means operated by said element in moving toward filling position for effecting movement of said receptacle on said carriage to a position in which its contents discharge, said receptacle when in said last-named position extending into a position in which said element in ascending moves said receptacle on said carriage out of said last-named position and through the medium of said receptacle releases said carriage for descent to a position in which said receptacle is charged from said hopper.

40. 11. In material-elevating apparatus, the combination of a hopper for the material to be elevated and provided with an outlet, an upwardly traveling carriage, a receptacle for receiving and elevating material from said hopper and mounted on said carriage to move thereon into a position in which its contents may discharge therefrom, said carriage being movable into and out of a position in which said receptacle registers with said hopper-outlet, a movable element into which said receptacle discharges, means for actuating said carriage, means for moving said receptacle on said carriage, and means operating automatically to close said hopper-outlet in the movement of said receptacle out of registration with the latter and to open said outlet to said receptacle in the movement of the latter into registration with said outlet.

60. 12. In material-elevating apparatus, the combination of a hopper for the material to be elevated, a bucket for elevating the material, hoisting means for said bucket, a counter-weight for said bucket, an upwardly traveling carriage, a receptacle for receiv-

ing and elevating material from said hopper and mounted on said carriage to move thereon into a position in which its contents may discharge therefrom, and means actuated by said counter-weight in descending for moving said carriage into raised position.

13. In material-elevating apparatus, the combination of a hopper for the material to be elevated, a bucket for elevating the material, hoisting means for said bucket, a counter-weight for said bucket, an inclined guiding support, a carriage supported on and movable along said support, a receptacle for receiving and elevating material from said hopper and mounted on said carriage to move thereon into a position in which its contents may discharge therefrom into said bucket, and means actuated by said counter-weight in descending for moving said carriage into raised position.

14. In material-elevating apparatus, the combination of a hopper for the material to be elevated, a bucket for elevating the material, hoisting means for said bucket, a counter-weight for said bucket, the connections between said counter-weight and bucket being such that said counter-weight travels at a reduced speed compared with the bucket, an upwardly traveling carriage, a receptacle for receiving and elevating material from said hopper and mounted on said carriage to move thereon into a position in which its contents may discharge into said bucket, and means actuated by said counter-weight in descending for effecting the elevating of said carriage to elevate said receptacle for delivery into said bucket when moved relative to said carriage.

15. In material-elevating apparatus, the combination of a hopper for the material to be elevated, a bucket for elevating the material, hoisting means for said bucket, a counter-weight for said bucket, an upwardly traveling carriage, a receptacle for receiving and elevating material from said hopper and mounted on said carriage to move thereon into a position in which its contents may discharge therefrom, means actuated by said counter-weight in descending for moving said carriage into raised position, and means releasably holding said carriage in raised position when the counter-weight rises.

16. In material-elevating apparatus, the combination of a hopper for the material to be elevated, a bucket for elevating the material, hoisting means for said bucket, a counter-weight for said bucket, an upwardly traveling carriage, a receptacle for receiving and elevating material from said hopper and mounted on said carriage to move thereon into a position in which its contents may discharge therefrom, means actuated by said counter-weight in descending for moving said carriage into

raised position and means releasably holding said carriage in raised position when the counter-weight rises, and releasable by the action of said bucket in ascending, to permit 5 said carriage and receptacle to descend.

17. In material-elevating apparatus, the combination of a hopper for the material to be elevated, a bucket for elevating the material, hoisting means for said bucket, a 10 counter-weight for said bucket, an upwardly traveling carriage, a receptacle for receiving and elevating material from said hopper and mounted on said carriage to move thereon into a position in which its contents may discharge therefrom, means actuated by said counter-weight in descending for moving said carriage into raised position, and means operating responsive to the movement of said bucket for effecting movement of 15 said receptacle on said carriage to a position in which its contents may discharge therefrom.

18. In material-elevating apparatus, the combination of a hopper for the material to be elevated, a bucket for elevating the material, hoisting means for said bucket, a counter-weight for said bucket, an upwardly traveling carriage, a receptacle for receiving and elevating material from said hopper and 20 mounted on said carriage to move thereon into a position in which its contents may discharge therefrom, means actuated by said counter-weight in descending for moving said carriage into raised position, and means 25 actuated by said bucket in descending for moving said receptacle on said carriage into a position in which its contents may discharge therefrom.

19. In material-elevating apparatus, the combination of a hopper for the material to be elevated, a bucket for elevating the material, hoisting means for said bucket, a counter-weight for said bucket, an upwardly traveling carriage, a receptacle for receiving and elevating material from said hopper and mounted on said carriage to move thereon into a position in which its contents may discharge therefrom, means actuated by said counter-weight in descending for moving 45 said carriage into raised position, and means actuated by said bucket in descending for moving said receptacle on said carriage into a 50

position in which its contents may discharge therefrom, said bucket operating in ascending toward dumping position to move said 55 receptacle on said carriage out of a position in which its contents discharge therefrom.

20. In material-elevating apparatus, the combination of a hopper for the material to be elevated, a bucket for elevating the material, hoisting means for said bucket, a counter-weight for said bucket, an upwardly traveling carriage, a receptacle for receiving and elevating material from said hopper and mounted on said carriage to move thereon 60 into a position in which its contents may discharge therefrom into said bucket, means operated by said counter-weight in descending for moving said carriage from a position in which the receptacle thereon receives a 65 charge from said hopper into raised position, means releasably holding said carriage in raised position during the ascent of said counter-weight, and means operated by said bucket in moving toward filling position, to 70 charge from said hopper into raised position, means releasably holding said carriage in raised position during the ascent of said counter-weight, and means operated by said bucket in moving toward filling position, to 75 move said receptacle on said carriage into a position in which its contents may discharge into said bucket, the last referred to position occupied by said receptacle, relative to said bucket, being such that said bucket in 80 ascending moves said receptacle on said carriage out of a position in which its contents discharge and, through the medium of said receptacle, releases said carriage for descent to a position in which said receptacle is 85 charged from said hopper.

21. In material-elevating apparatus, the combination of a hopper for the material to be elevated, a bucket for elevating the material, hoisting means for said bucket, a counter-weight for said bucket, the connections between said counter-weight and bucket being such that said counter-weight travels 90 at a reduced speed compared with the bucket, an upwardly traveling carriage, a receptacle 95 for receiving and elevating material from said hopper and mounted on said carriage to move thereon into a position in which its contents may discharge therefrom, and means actuated by said counter-weight in descending for moving said carriage into 100 raised position.
